UNITED STATES PATENT OFFICE.

HERMON E. ROBBINS, OF MILLGROVE, INDIANA.

AUTOMATIC REGISTERING-FAUCET.

1,085,702.

Specification of Letters Patent.

Patented Feb. 3, 1914.

Application filed April 17, 1913. Serial No. 761,888.

To all whom it may concern:

Be it known that I, HERMON E. ROBBINS, a citizen of the United States, residing at Millgrove, in the county of Blackford and State of Indiana, have invented a new and useful Automatic Registering-Faucet, of which the following is a specification.

The present invention relates to improvements in automatic registering faucets, the particular faucet being especially adapted for use in connection with tank wagons from which oil or other fluids are retailed, one object of the present invention being the provision of means upon which the bail or handle of the receptacle is hung and which according to the amount of liquid to be dispensed, will be actuated at the proper time to register, there being provided an auxiliary alarm means to give an audible alarm so that the party dispensing will know exactly when the desired amount is within the receptacle.

A further object of the present invention is the provision of a registering attachment for tank wagon spouts, in which means for receiving the bail of the dispensing can is so constructed and adjusted, as to register only when a sufficient quantity of the fluid is within the can, the registering device actuated by the weight of the can and the predetermined amount of liquid therein operating in one direction so as not to be returned in a retrograde direction, the registering dial being disposed within the casing and concealed so as not to be tampered with.

35 A still further object of the invention is the provision of adjustable means whereby various quantities of liquid may be measured with the same faucet and registering device.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the complete faucet with the pres-

ent invention in operable relation thereto, the electrical alarm being shown in diagram. Fig. 2 is a similar view to Fig. 1 with the spout of the faucet broken away and the casing over the registering dial removed. Fig. 55 3 is an enlarged detail perspective view of the can receiving lever and the pawl actuated thereby. Fig. 4 is a section taken on line 4—4 of Fig. 1. Fig. 5 is an enlarged detail view showing the electrical connection for 60 closing the circuit to the audible alarm.

Referring to the drawings, the numeral 1 designates the faucet, which is of the usual construction employed upon tank wagons, the same being provided with the manually 65 controlled valve stem 2 and with the bucket receiving lug 3. One side of the faucet is flattened as at 4 and is provided with the interiorly threaded cylindrical boss 5 which provides a journal for the registering dial 6, 70 the washer 7, the disk 8 and the screw 9 being secured to the boss 5, as clearly shown in Fig. 4, so that the dial is properly assembled and prevented outward displacement while the disk 8 with the central apertured portion 75 of the casing 10 provides the concentric circular slot 11 for the movement of the dial operating stud or pin 12. A pawl 14 is mounted upon the pin 13 within the casing 10 and its spring 14' holds such pawl in engagement with the peripheral teeth 15 of the registering disk 6 so as to prevent a retrograde movement of the disk. The other face of the disk 6 is provided with the scale numbers 16 which indicate the number of filled 80 cans or dispensers that have been filled through the faucet 1, one number at a time of the scale, being visible through the sight aperture 17 of the casing 10, as clearly shown in Fig. 1, this number corresponding to the 90 last manipulation of the mechanism, the operating means of which consist of the pin 18 which is disposed in the rear portion of the lug 3 of the faucet and forms a pivot for the apertured lugs 19 of the receptacle receiving 95 member or lever 20. The bail of such receptacle is adapted to be disposed upon the free end 21 thereof directly above the lug 3, as is the usual custom and thus compresses the spring 22, which is of such a tension as to 100

be unaffected by an empty can. An arm 23 is carried by the lever 20 and projects in an opposite direction to the can receiving member 21, while a flat spring 24 is connected to the member 20 by means of the screw 24', its free end extending slightly above, but substantially parallel to, the arm 23 to be engaged by the lower end 38 of the adjusting screw 37, so that the tension of the spring 24' 10 may be adjusted according to the predetermined amount of oil that it is desired to register with the present apparatus.

The two springs 22 and 24, as before stated, oppose the weight of the can placed upon the free end 21 of the lever 20, but as the can is approaching the predetermined amount desired, the free end 21 will be lowered and when the predetermined amount has been reached, such springs will 20 be compressed and the stud 25 abutting the reduced end 26 and carrying thereon the pivoted operating pawl 27, will be elevated, so that the hooked end 29 of the pawl 27 which is held toward the peripheral teeth 15 of the 25 registering disk 6, will be elevated and thus rotate the pawl the distance of a tooth, or so as to present the next succeeding number through the sight aperture 17 of the casing 10. The removal of the can from the end 21 of the lever 20, will free the lever to the action of the springs 22 and 24, which will cause the arm 23 to be depressed and the pawl 27 to be lowered to engage the next succeeding tooth below for the next succeeding registering operation.

By means of the screw 37, it is evident that the tension of the spring 24 may be varied so that the lever 20 will be actuated at any predetermined amount, as for instance, one, two, three, four or five gallon capacities, thus causing the pawl 27 to be operated to move the registering disk 6 as soon as the desired amount of oil is within the can. In ordinary practice this adjustment is for five gallons which is the usual size can be employed in connection with dispensing of oil from tank wagons.

In order to provide an audible alarm to indicate to the party dispensing when the registering device has operated and at the same time acts as a warning to advise him when the predetermined amount of oil is within the can, an electrical alarm is employed in connection with the arm 23 of the lever 20, the switch or connecting point being so housed or concealed as to prevent sparking, so that the present device may be used in connection with a volatile oil, such as gasolene. In order to accomplish this, a stud or pin 30 is carried by the headed portion 26 of the stud 25, and is disposed when the lever is moved upwardly with the head 26 provided in the arcuate slot 40 of the casing 10, to enter the insulating tube

41 which has incased therewith the terminal 36, which is thus insulated from the body of the faucet so that the circuit, which is grounded at 31, will not be short circuited. It will thus be seen that the circuits when closed at contacts 30 and 36 will be as follows: the body of the faucet, the binding screw 31, the conductor 32, the audible alarm 33, the battery 34, the conductor 35, the insulated contact 36, the contact stud 30 and ground through the faucet body and metal portions. By this means it will be seen that when the stud 30 has been elevated to its full extent, due to the depression of the outer end 21 by the filled can, that consonantly with the rotation of the dial 6, the circuit 80 will be closed, so as to operate the audible alarm 33 and indicate to the party dispensing that the predetermined amount is within the can and also that the disk 6 has registered.

From the foregoing description, taken in connection with the drawings it is evident that an automatic registering device as herein set forth may be readily applied to the usual oil tank faucets now in use, it simply being necessary to place the dials upon one side of the faucet which may or may not be provided with a plane surface, the lever 20 being pivoted to the rear of the can bail receiving lug 3 while the adjusting screw 37 95 is disposed in the casing in the position to bear upon the free end of the flat spring 24, such action in conjunction with the spring 22 adjusting the lever 20 so that the same is depressed for varying predetermined 100 quantities of oil so that the registering dial will be operated as desired and indicate the number of filled cans dispensed through the particular faucet. By means of the alarm mechanism, the same is provided 105 whereby the party dispensing may be warned in sufficient time to operate the valve stem 2 to cut off the flow of oil to the can. It is also evident that the empty can may be swung upon the lever 20 without affecting 110 the registering mechanism, the effect upon the dial 6 being only at the final filling of the can, or when approaching the predetermined amount.

What is claimed is:

The combination with a liquid dispensing faucet, of a registering mechanism therefor, including a dial rotatably mounted upon the faucet, said dial being provided with a plurality of peripheral teeth, a retrograde movement preventing pawl engaging the teeth, a can supporting lever pivotally connected to the faucet, a resilient support therefor disposed to oppose the filling can, a spring actuated pawl pivotally connected to the lever and disposed to operably engage the teeth of the dial to impart a step-by-step movement to the dial due to the

operation of the lever by the filling can, and
a screw mounted in the body of the faucet
and engaging the supporting lever for vary-
ing the resilient support of the lever, where-
5 by varying predetermined amount of fluid
may operate the lever.

In testimony that I claim the foregoing

as my own, I have hereto affixed my signa-
ture in the presence of two witnesses.

HERMON E. ROBBINS.
